CLAIM

The ornamental design for an electric cord lockbox, as
shown and described.

DESCRIPTION

FIG. 1 is a rear and upper right perspective view of an
electric cord lockbox showing my new design with the
lid in the open position;

FIG. 2 is a front elevational view of an electric cord
lockbox showing my new design with the lid in the
closed position and on a reduced scale;

FIG. 3 is a rear elevational view thereof;

FIG. 4 is a top plan view thereof;

FIG. 5 is a bottom plan view thereof; and,

FIG. 6 is a left side elevational view thereof.

The broken line showing of the plug in FIG. 1 is in-
cluded for the purposes of illustrating environmental
elements only and forms no part of the claimed design.
